OIL WELL EQUIPMENT

John R. Yancey, Houston, Tex., assignor to Gray
Tool Company, Houston, Tex., a corporation of
Texas

Application August 9, 1941, Serial No. 406,176

3 Claims. (Cl. 166—15)

This invention relates to oil well foundation equipment and auxiliary devices enabling the operator to complete the well in the most economical manner yet with the assurance of being able to safely handle any situation which may arise.

The invention is particularly useful under conditions such as exist, for example, in the West Texas field where separate gas sands independent of the regular producing horizon may or may not be encountered above the regular producing horizon. Starting with the foundation equipment provided in accordance with the invention, the operator can proceed with the auxiliary equipment of the invention as the encountered conditions may dictate, much of this auxiliary equipment being in the nature of salvageable accessories. Suitable equipment and procedural steps for carrying out the invention are shown by way of example in the accompanying drawings with reference to which the description will proceed.

In the drawings:

Figure 1 is an elevation partly in section of the upper end of a casing, a head secured to the casing, and a hold-down ring on the head;

Figure 2 adds to Figure 1, in elevation, and partly in section, control equipment including a drilling master valve and a blowout preventer;

Figure 3 is a section through the hold-down ring and adjacent portions of the head and drilling master valve of Figure 2, the section being taken in a different plane from that of Figure 2 for the purpose of showing a preferred means of securing the parts together;

Figure 4 is an elevation partly in section showing the elements of Figure 2 with the control equipment and ring lifted away, and additionally showing an inner pipe and slips disposed around the latter ready to be moved to operative position;

Figure 5 is an elevation partly in section showing the slips of Figure 4 in operative relation in the head with the inner pipe cut off thereabove, and showing additionally a stuffing box about to be engaged with the inner pipe;

Figure 6 is an elevation partly in section showing the stuffing box of Figure 5 in operative disposition between the casing head and a superposed tubing head, and showing also control equipment superposed on the latter;

Figure 7 is a view like Figure 2, but showing an inner pipe and a stripper embracing the inner pipe above the control equipment;

Figure 8 is a fragmentary view showing an enlarged axial section of the stripper of Figure 7;

Figure 9 is a view like Figure 7, but showing the stripper seated in the casing head and engaged by the hold-down means;

Figure 10 is a view like Figure 9, but showing the control equipment lifted away from the hold-down ring and showing, additionally, slips surrounding the inner pipe above the ring;

Figure 11 is a view like Figure 10, but showing the slips operatively disposed in the stripper, the control equipment having been swung away and the inner pipe cut off above the hold-down ring, and additionally showing a stuffing box about to be engaged with the upper end of the inner pipe;

Figure 12 is a view like Figure 11, except that the stuffing box is shown operatively disposed between the hold down ring and a superposed tubing head;

Figure 13 is a view like Figure 11 except that the hold-down ring and a removable upper portion of the stripper are absent; and

Figure 14 is a view like Figure 13, but with the stuffing box operatively disposed between the casing head and a tubing head with control equipment on the latter.

As indicated at the outset, the purpose of the invention is to provide relatively simple equipment designed to take care of arising situations in the most economical manner and for the purpose of illustration herein it will be assumed that the contemplated conditions of operation are such as may be encountered in the West Texas field wherein upper gas sands may be struck. According to the invention, the simpler the operation the cheaper becomes the permanent assembly left on the well. In more involved operations, more equipment is required, but much of this equipment is salvageable.

Referring now to the drawings, and first to Figure 1, reference numeral 20 designates an outer casing which has been run in and cemented and has been equipped with a head 21 having an annular bolting flange 22 and an upwardly faced conical internal seat 23. Supported on flange 22 through the intermediary of a packing ring 24 is a hold-down ring 25 equipped with a number of radially disposed set screws 26 whose threaded inner ends are engaged in threaded bores in the ring 25 and whose outer ends are passed through stuffing boxes equipped with gland nuts as at 27. The outer ends of the screws 26 may be squared for engagement by a turning tool, their inner ends being beveled. The inner diameter of the ring 25 is substantially the same as the maximum diameter of seat 23, the outer diameter of

the ring being substantially the same as the outer diameter of flange 22, as here shown.

In Figure 2, control equipment including a drilling master valve 28 and a blowout preventer 29 is shown superposed on ring 25, the drilling master valve having a flange 30 of the same diameter as ring 25 and the casing head flange 22, a packing ring 31 being interposed between flange 30 and ring 25.

The casing head, hold-down ring, and control equipment constitute foundation equipment from which the operator may work to take care of the encountered conditions in the simplest and most economical manner. The control equipment includes essentially the drilling master valve and desirably a blowout preventer, as shown. If desired, a second blowout preventer may be added.

In Figure 2, the drill D is about to be lowered for the drilling-in operation. Depending on whether or not the gas sand is struck, it may be that after the inner string of pipe is lowered the operator will wish to lift off the control equipment and therewith the ring 25, or to lift off the control equipment leaving the ring 25 secured to the casing head. In order that this choice may be exercised, I provide independent means for securing the ring to the casing head and for securing the control equipment to the ring. An example of such an arrangement is shown in Figure 3.

Referring to Figure 3, the ring 25 is provided with a number of bores as at 32, these bores being threaded throughout, and being parallel to the axis of the ring and equally spaced apart on a common circle. The casing head flange 22 and the flange 30 of the drilling master valve are provided with unthreaded bores registering with the bores 32 of ring 25. Threaded studs as at 33 are passed through the bores of flange 22 and screwed half-way into the bores 32, nuts as at 34 being threaded on the lower ends of the studs so that ring 25 is securely attached to the casing head. Threaded studs as at 35 are passed through the bores of flange 30 and screwed into the bores 32 until they strike studs 33, nuts 36 being applied to the upper ends of studs 35 so that the drilling master valve is securely attached to ring 25.

If everything goes well and upper gas sand is not encountered before reaching the oil sand, the procedure disclosed in Patents 2,082,413 or 2,117,-444, respectively issued on June 1, 1937, and May 17, 1938, to Robert A. Mueller and myself, may be followed and since there will now be no occasion to use the hold-down ring 25, the studs 33 can be removed so that the ring will be lifted away with the control equipment.

In Figure 4 is it assumed that no gas has been encountered, but that the pipe 37 has stuck off-bottom. Ring 25 has been lifted away with the control equipment and slips 38 applied to the pipe. A slip type hanger such as is disclosed in Patent No. 2,207,469, issued to Richard P. Roye, July 9, 1940, could be employed and a weld could be formed in accordance with this last-mentioned patent, since no gas has been encountered. In Figure 5 the slips are shown engaged with seat 23 of the casing head and supporting the pipe which has been cut off a distance above the head. Reference numeral 39 designates a stuffing box which is about to be applied to the upper end of the pipe, this stuffing box including, for example, a neoprene impregnated cotton fabric packing cup 40 so as to be able to afford a relatively long lived seal.

Figure 6 shows the stuffing box 39 operatively

engaged with the pipe 37 and clamped between the casing head 21 and a tubing head 41 on top of which is secured control equipment including a drilling master valve 42 and a blowout preventer 43, the drill D' being about to be lowered through the equipment for the next drilling operation. Completion of the well will be assumed to follow in the ordinary manner.

It will now be assumed that a stratum of gas sand has been encountered above the oil sand. After the inner casing has been run in and cemented, it may be found that due to low pressure of the sand it has been effectively sealed off by the cement and whether this is the case can, of course, be determined at the casing head. However, if the gas pressure is high enough or the drilling mud is light the gas will cut the cement thereabove rendering the cement ineffective as a seal. It is to be understood that the gas sand referred to may be anywhere from 50 to 2000 feet or more above the regular producing sand.

In Figure 7 the foundation equipment is exactly the same as in Figure 2, including the casing head 21, the hold-down ring 25, and the control equipment. In this case, however, it is assumed that the upper gas sand has been encountered. A stripper S has been applied to the pipe, this stripper, as particularly shown in Figure 8, comprising a central conical ring portion 44 having a lower threaded flange with which is engaged a ring portion 45 carrying a downwardly and inwardly converging rubber skirt 46 of flexible rubber, neoprene, or the like, which seals against the pipe 47, Figure 7. The stripper also includes an upper ring portion 48 engaged with a threaded internal flange of ring 44. Ring 48 is substantially cylindrical, whereas the lower rings are tapered substantially as the casing head seat 23.

With the set screws 26 retracted as in Figure 7, the stripper is lowered through the control equipment and ring 25 and landed on seat 23, the screws 26 being then screwed inwardly so as to engage an upper, outer tapered portion 49 of ring 48 so that the stripper is firmly seated and held down, an outer seal being effected by sealing rings carried by ring portion 44. The pipe 47 is now lowered into the well with the stripper acting as the principal control means, preventing the escape of gas from between the inner and outer casings. Pressure may be relieved through the vents (side outlets) in the casing head, if the pressure between the casing strings is strong enough to overload the stripper.

The pipe 47 is run into the well until the required level is reached or until conditions arise which stop further downward movement thereof. After the pipe has been cemented, studs 35 are removed, leaving ring 25 secured to the casing head, the control equipment is elevated, and slips 50 are disposed about the pipe 47, as shown in Figure 10. Since ring 25 is, as stated, secured to the casing head, it is still effective to hold down the stripper.

In Figure 11 the slips 50 are shown seated in the bowl 51 of the stripper S. The pipe has been cut off a distance above ring 25 after the operative disposition of the slips in the bowl, and a stuffing box 52, exactly like stuffing box 39, is about to be applied. Figure 12 shows the stuffing box operatively engaged with the pipe and clamped between ring 25 and the flange 53 of a superposed tubing head 54. The flange 52a of stuffing box 52 is of less diameter than the circle on which the bores 32 of ring 25 are located and, consequently, does not interfere with the place-

ment of the long studs 55 by which flange 53 is secured to ring 25. Studs 55 replace studs 35, Figure 3, in view of the greater length required.

The stuffing box is used to supplement the stripper and provide a seal which will not deteriorate during the normal life of the well. The stripper skirt 46 being made of rubber, neoprene, or the like, will not last as long as the well is likely to flow and, therefore, must be supplemented by a more permanent seal as provided by the stuffing box. Further, the stripper is likely to be overloaded by the closed in well pressure and must be supplemented by the stuffing box in order to maintain an effective seal against pressure from above or below. It is assumed that completion will proceed in the ordinary fashion.

In the procedure just described, it has been assumed that it has not been feasible to remove ring 25. However, if the pressure between the strings is not great enough to stretch the inner string of pipe, and if the weight of the casing resting on the slips in the stripper bowl is great enough to hold the stripper down, ring 25 is salvaged as is also the upper ring portion of the stripper S. In Figure 13 it will be seen that these parts have been removed prior to the application of the stuffing box, thus effecting a considerable saving. The set up shown in Figure 14 is like that of Figure 6 except that the slips of the latter figure are replaced by the lower portion of the stripper and the slips carried thereby.

From the above it will be seen that by using the described foundation equipment the procedure can move in the required direction and that in any event the salvaging of parts for reuse is possible, thus affording the most economical operations. I, of course, do not limit myself necessarily to the described details, the scope of the invention being determined in the following claims.

I claim:

1. The combination with oil well foundation equipment including a casing head, said head having an annular internal upwardly facing seat, control equipment including a drilling master valve above said head, and a separate ring disposed between the master valve and head, said ring having inwardly and outwardly adjustable hold-down means and an available internal diameter substantially as large as the maximum diameter of said seat, of a stripper insertable through said control equipment and ring around an inner pipe to said seat and maintainable on the latter by said hold-down means, said strip-

per including a bowl for the reception of slips, slips disposable in said bowl for the support of said pipe, and means removably securing said ring on said head independently of the control equipment so that the latter may be removed and replaced by a head for another pipe while the stripper is held down by said ring.

2. The combination with oil well foundation equipment including a casing head, said head having an annular internal upwardly facing seat, control equipment including a drilling master valve above said head, and a separate ring disposed between the master valve and head, said ring having inwardly and outwardly adjustable hold-down means and an available internal diameter substantially as large as the maximum diameter of said seat, of a stripper insertable through said control equipment and ring around an inner pipe to said seat and maintainable on the latter by said hold-down means, said stripper including a bowl for the reception of slips, slips disposable in said bowl for the support of said pipe, means removably securing said ring on said head independently of the control equipment so that the latter may be removed and replaced by a head for another pipe while the stripper is held down by said ring, and a stuffing box disposable between said ring and the second head for forming a permanent seal with the first pipe.

3. The combination with oil well foundation equipment including a casing head, said head having an annular internal upwardly facing seat, control equipment including a drilling master valve above said head, and a separate ring disposed between the master valve and head, said ring having inwardly and outwardly adjustable hold-down means and an available internal diameter substantially as large as the maximum diameter of said seat, of a stripper insertable through said control equipment and ring around an inner pipe to said seat and maintainable on the latter by said hold-down means, said stripper including a bowl for the reception of slips and including a separable annular portion above said bowl engageable by said hold-down means, slips disposable in said bowl for the support of said pipe, and means removably securing said ring on said head independently of the control equipment so that the latter may be removed and replaced by a head for another pipe while the stripper is held down by said ring.

JOHN R. YANCEY.
